UNITED STATES PATENT OFFICE.

JACOB GOLDSTEIN, OF WEST HAZLETON, PENNSYLVANIA, ASSIGNOR OF ONE-HALF TO
JAMES J. MUNLEY, OF WEST HAZLETON, PENNSYLVANIA.

ROTARY TOOTHRUSH.

1,330,525.

Specification of Letters Patent. Patented Feb. 10, 1920.

Application filed January 27, 1919. Serial No. 273,378.

To all whom it may concern:

Be it known that I, JACOB GOLDSTEIN, a citizen of the United States, residing at West Hazleton, in the county of Luzerne and State of Pennsylvania, have invented 5 certain new and useful Improvements in Rotary Toothbrushes, of which the following is a specification.

This invention relates to tooth brushes 10 and more particularly to rotary tooth brushes.

The primary object of the invention is to provide rotary brush elements arranged in parallel relation and adapted to be rotated 15 in opposite directions whereby both surfaces of the teeth may be cleaned by the brush elements.

The invention further aims to provide brush elements adapted to be actuated in 20 opposite directions and spaced apart sufficiently to permit the brush elements to be thrust into the user's mouth whereby the brushes may be engaged on opposite sides of either the upper or lower row of teeth 25 while the shafts are manually actuated to cause rotation of the brush elements in opposite directions.

Another object of the invention is to provide a rotary tooth brush having parallel 30 rotary brush elements and shields embracing portions of the brush elements whereby the inside of the user's mouth will not be injured or irritated, and also to effectively prevent the projection of saliva from the 35 mouth while the brushes are rapidly rotated.

The above and additional objects are accomplished by such means as are illustrated in the preferred embodiment and in the accompanying drawings, wherein like characters of reference denote like or corresponding parts throughout the several views:

Figure 1 is a perspective view of the device constructed in accordance with my invention.

Fig. 2 is a plan view of the same, parts being shown in section.

Fig. 3 is a section taken on the line 3—3 of Fig. 2, and

Fig. 4 is an end elevation,

Fig. 5 is a fragmentary plan view, partly in section, illustrating a modified form of the invention, and

Fig. 6 is a detail view of the same.

Referring to the drawing, wherein is illus-

trated the preferred form of my invention, in which like numerals of reference indicate like or corresponding parts throughout the several views, the frame 1 comprises a plate 2 having its longitudinal marginal edges rolled to provide sleeves 3 in parallel relation.

One end of the plate between the sleeve 3 is removed to provide a relatively long open space 4. Attached to the opposite end 65 of the frame is a gear housing 5 within which the gears 6 are arranged. The sleeves 3 contain the parallel shafts 7 which extend into the housing 5 and carry the gears 6. One end of one shaft is extended as indicated at 8 and is shaped to provide a crank 9 which may be manually actuated in order to rotate the shaft whereby both shafts will be simultaneously actuated in 70 opposite directions by virtue of the intermeshing gears 6.

At the opposite ends of the sleeves, the shafts are extended and have mounted on the extended portions, the brush elements 10 constructed in any preferred manner and 75 preferably consisting of stiff bristles such as are employed in the construction of tooth brushes. It will be noted that the brush elements 10 are relatively small in diameter and it will be obvious that they may be of 80 any preferred length. The shafts are disposed close enough together to cause the brush elements to be maintained in close proximity so that the teeth when received between the brushes will be thoroughly 85 cleansed when the brushes are actuated.

The elongated space 4 between the extended ends of the sleeves 3, will permit the rotary brushes to be extended into either side of the mouth, the teeth being received 90 between the brush elements as the device is manipulated by the operator. It will be noted, therefore that both the front and back surfaces of the teeth will be thoroughly 95 cleansed and the crank may be rotated in either direction so that the surfaces will be brushed upwardly or downwardly in accordance with the most approved method of brushing the teeth.

In Figs. 5 and 6 I have illustrated a slight 100 modification of the device wherein the shields 12 are provided for the brushes. Each shield consists of a transversely curved plate 13 of a length equal to the length of the brush elements, this plate forming an 105

integral part of an extension 14 formed at the end of each sleeve. This extension is bent at right angles outwardly from the sleeve as shown so that when the shield is 5 in position it partially embraces the outer portion of the brush element.

Therefore when the device is placed within the user's mouth, the shield will engage the cheek on the inside thereof. While the 10 device is in use on the front teeth, the shield will serve to prevent projection of saliva from the mouth during the rapid rotation of the brushes.

The foregoing description and accompanying drawings have reference to what might 15 be considered to be the approved or preferred form of my invention. I desire it to be understood that I may make such changes in the construction, combination 20 and arrangement of parts, materials dimensions, et cetera as may prove expedient and fall within the scope of the appended claims.

Having thus fully described my invention 25 what I claim as new and desire to secure by Letters Patent, is:—

1. A rotary tooth brush of the class described comprising a frame, said frame pro-

vided with a web plate, sleeves integrally mounted upon the marginal edges of said 30 plate, a relatively long open space provided at the ends of said sleeve, shafts mounted within said sleeves, means mounted on the ends of said shafts to rotate the latter in opposite directions, and rotary tooth brush 35 elements mounted on the opposite ends of said shafts.

2. A rotary tooth brush of the class described comprising a frame, said frame provided with parallel sleeves held in spaced 40 relation by a web plate integrally connected therebetween, a relatively long open space provided at one end of said sleeve, said web plate adapted to extend beyond the other end of said sleeve and to be bent at right 45 angles, shafts mounted within said sleeves, gears carried by one end of said shafts, said gears adapted to mesh and to be manually operated by a crank, a housing provided around said gears and integral with the 50 right angular portion of said web plate and rotary tooth brush elements mounted on the opposite end of said shafts.

In testimony whereof I affix my signature.

JACOB GOLDSTEIN.
